UNITED STATES PATENT OFFICE.

IVY E. WRIGHT, OF CHARLOTTESVILLE, INDIANA.

BARBED-WIRE FENCE.

SPECIFICATION forming part of Letters Patent No. 245,256, dated August 2, 1881.

Application filed April 30, 1881. (No model.)

To all whom it may concern:

Be it known that I, IVY E. WRIGHT, of Charlottesville, in the county of Hancock and State of Indiana, have invented certain new and useful Improvements in Barbed-Wire Fences; and I do hereby declare that the following is a full, clear, and exact description of the invention, which will enable others skilled in the art to which it appertains to make and use the same, reference being had to the accompanying drawings, which form a part of this specification.

In the annexed drawings, Figures 1 and 2 are views of twisted-wire fences having the movable barb attached thereto embodying my invention. Fig. 3 is a view of the barb detached.

The object of my invention is to attach a barb on one of the strands of a twisted fence-wire, and bend said strand over the junction of the eyes of the barb to prevent longitudinal movement of the same, but at the same time the barb will have a vertical movement thereon, and is limited by the lower strand of the twist, which passes outside of the barb; and it consists in the construction and novel means of attaching the barb in relation to the parts of the twisted wire, as hereinafter shown, described, and particularly pointed out in the claim.

In the accompanying drawings, the letter A designates the barb, bent from a stout piece of wire to form eyes a, which project in opposite directions in a straight line with each

other, and having their pointed ends lapped 35 side by side at the lower junction of said eyes and extending out in opposite directions therefrom. The barb is then passed on the upper wire, b, which is bent over the junction of the eyes a, to prevent longitudinal movement of 40 the same, with the pointed ends below and out of contact with said wire, which allows the barb to vibrate on either side of the same. The lower wire, b', is then intertwined or twisted with the wire b, which passes outside 45 of the barb and limits the turning movement of the barb by means of the pointed ends coming in contact with the said wire b', thus enabling the animal to free itself from the barb without danger of serious laceration, so com- 50 monly the result when stock come in contact with the fixed barbs.

Having described my invention, what I claim is—

The barb A, formed of a single piece of wire 55 and bent upon itself to form two loops with the sharp ends projecting in opposite outward directions, the wire b passing through said loops and twisted with a supplemental wire to hold the barb in position, as and for the pur- 60 poses set forth.

In testimony that I claim the foregoing as my own I have hereto affixed my signature in presence of two witnesses.

IVY E. WRIGHT.
